(57) **CLAIM**

We claim the ornamental design for a nasal dilator, as shown and described.

DESCRIPTION

FIG. 1 is an isometric top front view of a nasal dilator;
FIG. 2 is an isometric top rear view thereof;
FIG. 3 is a front view thereof;
FIG. 4 is a right side view thereof;
FIG. 5 is a rear view thereof;
FIG. 6 is a left side view thereof;
FIG. 7 is a top view thereof; and,
FIG. 8 is a bottom view thereof.
The broken lines in the drawings illustrate portions of the design that form no part of the claim.
